C. THOMPSON

WINDOW SASH SECURING MEANS

Filed April 5, 1926

UNITED STATES PATENT OFFICE.

CALVIN THOMPSON, OF VANCOUVER, BRITISH COLUMBIA, CANADA.

WINDOW-SASH SECURING MEANS.

Application filed April 5, 1926. Serial No. 99,920.

This invention relates to a means for automatically securing a slideable window sash in the closed position and may also be used for sustaining the sash at any desired position of elevation, in which case the device requires to be manually operated, while in the closed position the action is automatic.

The device also prevents the sash rattling in its frame.

10 These results are attained by a small eccentric which is mounted on the stile of the sash and is held by a spring in light frictional engagement with the window frame. The engagement of the eccentric with the frame 15 being above the pivot on which the eccentric is mounted, any attempt to move the sash upward will tend to draw the larger dimension of the eccentric between the pin on which it is mounted and the facing of the 20 window frame, whereby the sash is automatically secured against being opened from without.

From within the room the eccentric can be 25 manually rotated to withdraw the upper part of it from its frictional engagement with the facing when the window can be lifted to any desired height and if the eccentric is then rotated to bring the major part of it into engagement with the facing of 30 the window frame below the pivot on which the eccentric is mounted, the frictional engagement of the eccentric will tend to draw the larger dimension between the pivot pin and frame and sustain the sash at the 35 desired elevation in its frame.

The invention is fully described in the following specification, reference being made to the drawings by which it is accompanied, in which:

40 Fig. 1 is a face view of the device with the cover plate removed as applied to the stile of a window sash to engage the facing strip of the slideway in which the sash moves, and hold it closed, that is, against upward 45 movement, the dot and dash lines indicating the position of the device in the sustaining position.

Fig. 2 is a cross section of the window sash in its slideway showing the device in 50 plan, and

Fig. 3 is a cross section of the device on the line 3—3 in Fig. 1.

In these drawings 2 represents the stile of the window sash, and 3 its lower rail,

while 4 is the slideway in the sash frame, 55 5 the partition strip of the slideway and 6 the inner facing of the sash frame.

On the inner face of the sash stile 3 is pivotally mounted on a pin 7 a hollow eccentric 8 having a cover plate 9 which fits a 60 recess in the open face of the eccentric and is retained against rotation by a key 10.

The cover plate 9 is secured by a pin 11 which passes through it and is threaded into the closed end or bottom of the eccentric. 65 A flat spring 12 has one end anchored at 13 to the pivot pin 7 and is coiled around it and the other end bent around the pin 11 to impart a rotational effort to the eccentric in a clockwise direction in Fig. 1 that will hold 70 the upper and larger side of the eccentric in light frictional engagement with the facing strip 5 of the sash slideway that, when attempt is made to lift the sash 2, the friction tends to rotate the eccentric 8 on its pin 7 to move the larger part of the eccentric between the pin 7 and the sash facing strip 5, and will thereby prevent the sash being 75 lifted until the eccentric is manually rotated in the opposite direction to withdraw it from 80 engagement with 6. Thus it will be noticed that the spring 12 constitutes a means tending to move the eccentric member 8 toward or from the sash frame accordingly as said member 8 is located for preventing upward 85 movement of the window or downward movement of the window respectively.

When the window is elevated and the eccentric placed in the position shown by the dot and dash lines in Fig. 1, the frictional 90 engagement of the eccentric against the member 6, plus the weight of the window, will prevent the spring returning the eccentric to its normal position shown in full lines in Fig. 1. In order then to release the eccentric and permit the spring to act, it is 95 only necessary to lift the window slightly to relieve the weight on the eccentric.

The window sash, when closed, will be 100 automatically secured and the stronger the effort to lift it the more tightly will it be held.

When it is desired to raise the window the eccentric is manually rotated to bring it 105 away from frictional engagement with the facing 6. The sash may then be lifted and, as shown by the dot and dash lines in Fig. 1, the eccentric may be rotated to bring the

heavier side below the pin 7 and into contact with 6 when the weight of the sash will be sustained.

The outer circumferential surface of the 5 eccentric is suitably provided with a friction area as for example a band 14 of soft rubber placed around the periphery of the eccentric to afford the required grip to draw the eccentric into sustaining contact.

10 The device is simple and inexpensive and can be much more readily applied than sash cords and weights, and can be applied without modification or change to existing window sashes.

15 In either position the securing device will prevent rattle of the sash in its frame.

Having now particularly described my invention, I hereby declare that what I claim as new and desire to be protected in by Letters Patent, is:

20 1. A means for securing a window sash in its frame, said means comprising a relatively shallow hollow cylinder, a pin secured to the stile of the sash on which pin the hollow cylinder is eccentrically mounted, a spring one end of which is secured to the pin about 25 which the cylinder is rotatable which spring after coiling around the pin is connected to the inside of the cylinder to lightly hold the larger side of the cylinder in light frictional 30 engagement with the sash frame above the pin on which it rotates that upward movement of the sash will tend to draw the larger part of the cylinder between the pin and the sash frame and secure the sash.

35 2. A means for securing a window sash in its frame, said means comprising a relatively shallow cylinder body open at one end and having its other end projected to form a flange, a disk-like cap fitted over the open 40 end of said cylinder body, a screw passing through said cap and threaded into the cyl-

inder body for holding the cap in place, said cap having a projecting edge to form a flange, a friction band held on the peripheral portion of said cylinder body between said flanges, said cylinder and said cap having aligning apertures located eccentrically of the axis of the cylinder body, a screw passing through said apertures into the window 50 sash for securing the device thereto in a pivotal manner whereby said cylinder body may be turned through a complete revolution on said last named screw as an axis, a coil spring located within the cylinder body, 55 one end of which is attached to one screw and the other end attached to the other screw.

60 3. A means for securing a window sash against vertical movement in its frame, said means comprising a pin secured to the stile of the sash adjacent the sash frame, a cylindrical member eccentrically mounted on said pin, a spring means within said member which continuously tends to turn it in one direction on said pin to effect a normal engagement of the periphery of said member with the sash frame above the pivotal axis, said member being free to turn through a complete circle save as restrained by contact with the window frame whereby said member may be turned to engage the frame either above or below its pivotal axis to hold the window secured against movement upwardly or downwardly accordingly as the engagement is above or below said pivotal axis, said spring means functioning to effect the return of said member to its normal locking position in contact with the window frame when said member is released from contact with the frame at a place below said pivotal axis, substantially as specified.

70 In testimony whereof I affix my signature.
CALVIN THOMPSON.
